DIAL MECHANISM

Simon D. Rydstedt, Chicago, Ill., assignor to
Stewart-Warner Corporation, Chicago, Ill., a
corporation of Virginia

Application May 16, 1938, Serial No. 208,154

10 Claims. (Cl. 116—124.1)

This invention relates to a new and improved dial mechanism and more particularly to a pointer or indicator mechanism especially adapted for use with radio receivers of the type having a multiplicity of tuning ranges.

It has become customary in many modern radio receivers to provide separate inductances for different tuning ranges together with switching means for connecting the desired inductances in circuit with the tuning means of the set. With sets of this character dials are provided having separate adjacently located scales for the several tuning ranges. It is usual with such dials to provide a single rotating index finger 15 with arcuate scales or a single sliding index wire with rectangular scales. These index means extend over the several scales and are confusing to the user in that they do not definitely indicate the scale in use.

It is an object of the present invention to provide a new and improved scale and indicator mechanism.

It is a further object to provide a multiple scale device having indicators only one of which is in indicating relationship with a single scale in any adjustment of the device.

It is also an object to provide mechanism of this character in which indicators not in use are hidden from view.

It is another object to provide such dial mechanism which is automatically operable upon operation of the wave change mechanism of the set with which it is used.

It is an additional object to provide mechanism of this character adapted for use with arcuate scales or with rectilinear scales.

It is a further object to provide mechanism of this character which is simple in design, composed of but few parts and adapted for commercial production and use.

Other and further objects will appear as the description proceeds.

I have shown certain preferred embodiments in the accompanying drawings, in which—

Figure 1 is a front elevation of a radio receiver chassis with one form of my improved dial construction mounted thereon;

Figure 2 is a plan view of the construction of Figure 1, with the rear portion of the chassis 50 broken away;

Figure 3 is an enlarged face view of the indicator slide mechanism shown in Figures 1 and 2;

Figure 4 is a fragmentary section taken on line 4—4 of Figure 1;

Figure 5 is a fragmentary section taken on line 5—5 of Figure 3 on an enlarged scale;

Figure 6 is a face view of a different type of dial construction;

Figure 7 is an enlarged transverse section of 5 the form of construction shown in Figure 6;

Figure 8 is a view similar to Figure 6 and showing a modified form of construction; and

Figure 9 is a view similar to Figure 7 showing the construction of Figure 8.

Referring first to the form of construction shown in Figures 1 to 5, inclusive, the radio chassis base 11 has secured thereto the standards 12 and 13. These standards support the dial mechanism including the dial plate 14 and the guideway 15. The dial plate 14 has offset scale bearing portions 16, 17 and 18, as best shown in Figure 4. The pulleys 19 and 20 are carried from the standards 12 and 13 and these pulleys are provided with crank pins 21 and 22 which support a slide bar 23. The wave change mechanism is operated by knob 24 from shaft 25. This shaft 25 carries a pulley 26. The flexible cable 27 passes about pulley 26 and has its ends secured to the pulleys 19 and 20. The cable is 25 guided through eyelets 28 and 29 and is also guided by the small idler pulley 30.

The indicator slide 31 has its upper end fitted around the guideway 15, as shown at 32 in Figure 4, and is moved along the guideway by means 30 of the cable 33. This cable 33 passes around the idler pulley 34 at the right end of the chassis, as shown in Figure 1, and over the idler pulleys 35 and 36 at the upper left end of the chassis. The cable 33 also passes over the idler pulley 37 at the lower left portion of the dial assembly and both ends of the cable are secured to the cable drive drum 38 at the left of the chassis. It will be understood that the drum 38 is connected in any desired manner to the tuning 40 mechanism of the radio apparatus assembled on the chassis. This method of connection forms no part of the present invention and has not been shown in detail.

The indicator slide 31 carries a plurality of 45 rotatable indicators 39, 40 and 41 which are provided with the gears 42, 43 and 44. The indicators have the cup-shaped portions 45, 46 and 47, each of which is provided with oppositely spaced notches 48 and 49. The spring 50 is located adjacent the upper indicator 39 and is provided with a rounded end portion 51 adapted to selectively engage the notches 48 and 49 on the cup 45. The double spring 52 is provided with the oppositely extending rounded ends 53 and 54.

54 which are adapted to selectively engage the notches 48 and 49 in the indicator cups 46 and 47, respectively.

5 The indicator rack 55 is mounted on the indicator slide 31 by means of the rivets 56 and 57, which pass through the slotted openings 58 and 59 in the rack to permit it to have a limited longitudinal movement. The toothed edge 60 of the rack engages all three of the gears 42, 43 and 44. As best shown in Figure 4, the rack 55 is provided with the rearwardly extending lugs 61 and 62 which engage opposite edges of the slide bar 23. As is clearly shown in Figure 2, the pulleys 19 and 20 carrying the slide bar 23 are located in an inclined plane parallel to the location of the bar 23 as shown in Figures 2 and 4, so that upon rotation of the pulleys the bar 23 moves upwardly and downwardly parallel to the plane of the indicator slide 31.

20 Referring next to the form of construction shown in Figures 6 and 7, the circular dial 79 is provided with a plurality of arcuate scale bearing portions 71, 72 and 73 and with the central cap or cover 74. The shaft 75 is located concentrically of the dial scales in the rear thereof. This shaft will be connected in any desired manner to the movable tuning elements of the radio apparatus. The end of the shaft 75 carries the indicator arm 76, one side of which carries the 25 rotatable indicators 77, 78 and 79 which are provided with the gears 80, 81 and 82, respectively. The other portion of the arm carries a counterweight 93. The rack 83 meshes with all of these gears. The end of the rack 83 is provided with 30 upturned lugs 84 and 85 between which fits the end 86 of a bell crank lever 87 which is carried in the rotatable shaft 75. The other end of the bell crank 86 is connected by link 88 to the sliding member 89 which is adapted to be moved 35 axially along the shaft 75. The member 89 has a circumferential groove 90 in which fits the actuating arm 91. The arm 91 is secured to shaft 92, which may be connected in any desired manner to means for operating the indicators. It is 40 normally connected to the wave change mechanism of the apparatus.

The form of construction shown in Figures 8 and 9 is generally similar to that shown in Figures 6 and 7. The circular dial 100 is provided 45 with the outer dial scale portion 101 and with the intermediate cover portion 102. It is further provided with a double scale carrying portion 103 and a central cover portion 104. Separate scales will be located adjacent the opposite edges of the portion 103. The shaft 105 carries the indicator arm 106 which is counterweighted at 107. The arm 106 carries two indicators 108 and 109 which are provided with the gears 110 and 111, respectively. The rack slide 112 meshes with both gears 50 110 and 111, and at its end has the lugs 113 and 114 which engage the end 115 of the bell crank 116. This bell crank 116 is carried and operated 55 in the same manner as the bell crank 87 of Figure 7.

60 The form of construction of Figures 1 to 5 is operated automatically by the operation of the tuning and wave change controls of the radio set in the usual manner. It will be understood that by operating the tuning control of the set the indicator slide 31 will be moved back and forth so as to be opposite the indication on the proper scale corresponding to the adjustment of the tuning elements of the radio set. In the same manner, rotation of the knob 24 to bring into operation any desired wave range will automatically

move an indicator into indicating relationship with the scale corresponding to the wave band in use. The other indicators will be hidden by the scale carrying portions of the dial. Consequently the only indicator visible is that which points to the dial scale in use. This movement of the indicators is accomplished by means of the cable 27 connected to the pulleys 19 and 20.

5 In the form of construction shown, there are three wave ranges provided with separate scales 10 and indicators. It will be understood, however, that the device is capable of being used with two or more scales and indicators. With the parts in the position shown in the drawings, the intermediate scale 17 is in use and the indicator 40 15 extends over this scale and is visible. If the knob 24 is rotated in a counterclockwise direction, both pulleys 19 and 20 will be rotated in the same direction. This rotation through the crank pins 21 and 22 will move the slide bar 23 downwardly. 20 The parts are so related in size that when the knob 24 is turned sufficiently to bring into operation the next wave band, the bar 23 will have moved downwardly sufficiently so that the rack slide 55 by engagement with the gears 42, 43 and 25 44 on the indicators rotate each indicator through an arc of 90 degrees. This movement will rotate the indicator 49 until it is behind the scale 16 and is not visible. The indicator 39 will be rotated but will continue invisible. The indicator 41 will, by this 90 degree rotation, be brought into indicating relationship with the lower scale 18 and will be visible.

A clockwise rotation of the knob 24 will move the parts in the reverse direction. It will raise 35 the slide bar 23 and this will rotate all of the indicators 90 degrees in the clockwise direction. This will move the indicator 46 under the scale 16 and the indicator 41 will continue to be hidden by the scale 17. The indicator 39, however, will 40 pass out through the space at the upper edge of the scale 16 and will be in indicating relationship with that scale. It will be seen that all of these operations are carried out automatically by merely turning the usual knob to bring into 45 operation the desired wave range.

Referring next to the form of construction shown in Figures 6 and 7, the method of operation is generally similar to that described. The shaft 92 will be rotated when it is desired to 50 change from one wave range to another. With the parts in the position shown in the drawings, the indicator 77 is in indicating relationship with scale 73. Movement of the rack slide 83 to the left will move the indicator 77 behind the central shield 74. The indicator 79 will continue to be hidden by the scale 72. The indicator 78, however, will appear above the scale 72 and be in indicating relationship therewith. A further movement of the rack bar 83 to the left will bring 55 the indicator 79 into indicating relationship with the scale 71, while the other two indicators will be hidden.

The form of construction shown in Figures 8 and 9 is operated in the same manner as that 60 shown in Figures 6 and 7. The difference here is that a single indicator 108 serves at different times to coact with two different scales. With the parts in the position shown in Figures 8 and 9, the indicator 108 is in indicating relationship 65 with the scale 101. With the rack slide 112 moved to the left the indicator 108 will be hidden by the cover portion 102, while the indicator 111 will appear above the inner scale on the scale portion 103. With the rack slide 112 given further move- 70 75

ment to the left, the indicator 109 will again be hidden by the central cover 104. The indicator 108 will now have been moved through a total of 180 degrees and will appear above the outer scale upon the scale portion 103.

While I have shown and described certain preferred forms of my invention, these are to be understood to be illustrative only. While my invention has been described in connection with a 10 radio receiver it may also be used with other apparatus such as transmitters, test instruments and the like. I contemplate such changes and modifications as come within the spirit and scope of the appended claims.

15 I claim:

1. Radio dial mechanism comprising a plurality of spaced index scales, a plurality of indicators rotatably mounted adjacent the scales, and means for rotating an indicator into and out of 20 position above a scale and in indicating relationship therewith.

2. Radio dial mechanism comprising a plurality of spaced index scales, a plurality of indicators rotatably mounted adjacent the scales, and 25 joint operating means for rotating an indicator into position above a scale and in indicating relationship therewith and for rotating another indicator into position below a scale whereby the indicator is hidden by the scale.

30 3. Radio dial mechanism comprising a plurality of index scales, a plurality of pivots adjacent said scales, a plurality of rotatable indicators, one mounted upon each pivot and means for jointly rotating the indicators, the indicators being interconnected whereby such rotation 35 brings one indicator at a time into indicating relationship with a scale.

4. Radio dial mechanism comprising, in combination, a plurality of index scales, a multiple 40 indicator unit carrying a plurality of rotatable index pointers, means for moving the indicator unit relative to the index scales, and means for rotating the index pointers to bring one pointer at a time selectively in registration with a scale.

45 5. In radio apparatus, in combination a wave change device including a rotatable shaft, a dial mechanism comprising a plurality of index scales, a plurality of rotatable indicators, a gear on each indicator, a rack engaging said gears for moving the indicators into and out of indicating 50 relationship to the scales, and means operatively connecting the rotatable wave change shaft and the rack whereby upon wave change adjustment an indicator is in indicating relationship to the corresponding scale.

55 6. In radio apparatus, in combination, a wave change device including a rotatable shaft, a dial mechanism comprising a plurality of index scales, a plurality of rotatable indicators, a gear on each indicator, a rack engaging said gears for moving the indicators into and out of indicating 60 relationship to the scales, a slide engaging the rack, spaced pulleys carrying crank pins supporting the ends of the slide, and flexible means connecting the pulleys and the rotatable wave change shaft whereby upon wave change

adjustment an indicator is brought into indicating relationship with the corresponding scale.

7. In radio apparatus, in combination, a wave change device including a rotatable shaft, a dial mechanism comprising a plurality of index scales, 5 a plurality of rotatable indicators, a gear on each indicator, a rack engaging said gears for moving the indicators into and out of indicating relationship to the scales, a bell crank having one arm engaging the rack and link, and slide mechanism operatively connecting the bell crank and the rotatable wave change shaft whereby upon wave change adjustment an indicator is brought into indicating relationship with the corresponding scale.

15 8. In radio apparatus, in combination a wave change device including a movable shaft, a plurality of concentric arcuate scales having spaces adjacent their edges, a rotatable shaft concentric with the scales, indicator mechanism rotated by 20 the shaft comprising a plurality of indicators, and a sliding rack for rotating the indicators into and out of indicating relationship to the scales through the spaces adjacent the scales, the indicators not in such relationship being behind 25 the scales, and means carried in part by the concentric shaft operatively connecting the sliding rack and the movable wave change shaft whereby upon wave change adjustment an indicator is brought into indicating relationship with the 30 corresponding scale.

9. In radio apparatus, in combination a wave change device including a movable shaft, a plurality of parallel elongated scales having spaces adjacent their edges, a guideway parallel to the scales, an indicator slide movable along the guideway, a plurality of movable indicators carried by the slide, and means operatively connecting the movable shaft and the movable indicators for moving the indicators selectively into indicating 40 relationship with the scales whereby upon wave change adjustment an indicator is brought into indicating relationship with the corresponding scale.

45 10. In radio apparatus, in combination a wave change device including a movable shaft, a plurality of parallel elongated scales having spaces adjacent their edges, a guideway parallel to the scales, an indicator slide movable along the guideway, standards supporting the ends of the scales and guideway, pulleys carried upon the standards adjacent the ends of the guideway, crank pins on the pulleys, a slide bar carried by the crank pins and extending parallel to the guideway, a plurality of rotatable indicators carried by the 50 indicator slide, gears on the indicators, a rack carried by the indicator slide and engaging the gears, means connecting the rack and the slide bar whereby movement of the slide bar moves the rack, and flexible means connecting the movable wave change shaft and the pulleys whereby 55 upon wave change adjustment the pulleys are rotated, the slide bar and rack moved and the indicators rotated to bring an indicator into indicating relationship with the corresponding scale.
